TRACE CARRIER

Filed Jan. 5, 1929

By *Clarence O'Brien*
Attorney

UNITED STATES PATENT OFFICE

LEVI B. FOX, OF GRIMES, IOWA

TRACE CARRIER

Application filed January 5, 1929. Serial No. 330,640.

The present invention relates to a trace carrier and has for its prime object to provide a carrier of this nature which will preserve the traces and is strong and durable, 5 inexpensive to manufacture and thoroughly efficient and reliable in use.

With the above and numerous other objects in view as will appear as the description proceeds, the invention resides in certain novel 10 features of construction as will be herein-after more fully described and claimed.

In the drawing:

Figure 1 is an elevation of the trace carrier embodying the features of my invention, 15 Figure 2 is a sectional view taken substantially on the line 2—3 of Figure 1, and

Figure 3 is a section taken substantially on the line 3—3 of Figure 2.

Referring to the drawings in detail it will 20 be seen that the letter A denotes a strap of leather or other similar flexible material which is disposed about a strap B of metal. The strap B includes an elongated loop portion 5 which enlarges downwardly in a gradual manner, and at the upper end merging into a double ply portion 6 the upper end of which merges into the sleeve 7.

The strap A is disposed about the loop 25 portion 5 and along a double ply portion 6 and about the sleeve 7 and then overlapping itself as is indicated at 8 and rivets 9 passed through the straps A and B at the double 30 ply portion 6 and the overlapping portion 8 respectively.

An eye 10 is disposed between the sleeve 35 7. It is also to be noted that the edges of the strap B are flared outwardly as is indicated at 11 particularly shown to advantage in Figure 3 so as to eliminate friction and prevent the cutting of the trace.

It is thought that the construction, utility 40 and advantages of this invention will now be quite apparent to those skilled in this art without a more detailed description thereof.

It will be apparent that changes in the 45 details of construction, in the size, in the proportions, and in the combination and arrangement of parts as may be resorted to 50 without departing from the spirit or scope of

the invention as hereinafter claimed or sacrificing any of its advantages.

Having thus described my invention, what I claim as new is:

A trace carrier of the class described including a metal strap forming an elongated loop merging at its upper end in a double ply portion, said double ply portion in turn merging into an eye, and a leather strap covering said first mentioned strap. 55

In testimony whereof I affix my signature. 60
